BATTERY CARRIER

Alan A. Freedman, Williamsville, N.Y., assignor to
Bergman Tool Mfg. Co., Inc., Buffalo, N.Y.

Filed Dec. 3, 1970, Ser. No. 26,270

Term of patent 14 years

Int. Cl. D8—05

U.S. Cl. D8—14

Fig. 1.

Fig. 2.

Fig. 3.

Fig. 4.

Fig. 5.

FIG. 1 is a top plan view of a battery carrier, showing my new design;

FIG. 2 is a side elevational view thereof;

FIG. 3 is an end elevational view thereof;

FIG. 4 is an opposite end elevational view thereof; and

FIG. 5 is a bottom plan view thereof.

The side not shown is identical to the side shown in FIG. 2, except for those differences which are apparent from the drawings.

I claim:

The ornamental design for a battery carrier, substantially as shown and described.
